UNITED STATES PATENT OFFICE.

WALTER F. TROTTER, OF CHARLESTON, WEST VIRGINIA, ASSIGNOR, BY MESNE ASSIGNMENTS, TO THE JEFFREY MANUFACTURING COMPANY, A CORPORATION OF OHIO.

MINING-MACHINE.

1,127,698.

Specification of Letters Patent.

Patented Feb. 9, 1915.

Application filed September 12, 1907, Serial No. 392,601. Renewed February 3, 1912. Serial No. 675,343.

To all whom it may concern:

Be it known that I, WALTER F. TROTTER, citizen of the United States, residing at Charleston, in the county of Kanawha and State of West Virginia, have invented certain new and useful Improvements in Mining-Machines, of which the following is a specification, reference being had therein to the accompanying drawing.

10 This invention relates to improvements in mining machines, particularly to side cutting mining machines. It has been proposed heretofore to provide machines of this class with flexible draft devices adapted to propel the machine along the face of the coal and to guide it or hold it to its work. In some cases cables were to be used as the flexible draft and holding members, while there were others in which the functions of propelling and guiding the machine were to be performed by chains in connection with sprocket mechanisms or the like on the machines adapted to engage positively and rigidly with the chains. In one form of these 15 latter machines, for example, a single continuous chain is provided having one end fixed to an anchor or the like in advance of the machine and its other end fixed to an anchoring device on the rear side of the machine, while intermediate its ends the chain passes over sprocket drive mechanisms on the machine.

20 My invention contemplates, in its preferred form, the use of cables for propelling and guiding the machine and is intended to provide a machine in which are overcome certain disadvantages and difficulties that have heretofore been experienced in the use of side cutting machines, especially in room and pillar mining.

25 The nature and all of the various objects of the invention will be understood in detail from the following description in connection with the drawings.

30 Figure 1 is a plan view of a mining machine embodying my improvements; Fig. 2 is a section on the line 2—2, Fig. 1; Fig. 3 is a side elevation of the same; Figs. 4 and 4^a are enlarged sections on the line 4—4, Fig. 1, showing the operating mechanism and cutter frame, respectively; Fig. 5 is an enlarged section on the line 5—5, Fig. 1; Fig. 6 is an enlarged section on the line 6—6, Fig. 1; Fig. 7 is a plan view of the

inner portion of the cutter carrier and the 55 guiding mechanism for feeding it transversely to the coal face; Fig. 8 is a section on the line 8—8, Fig. 7, the adjustable jack being removed; Fig. 9 is a view partly in elevation and partly in section of the jack 60 stand and jack; Fig. 10 is a plan view on a smaller scale showing the mining machine arranged to feed transversely to the coal face at the beginning of a cut; Fig. 11 is a 65 plan view on a smaller scale showing the 65 mining machine and its operating parts arranged to feed laterally along the coal face; Fig. 12 is an enlarged side elevation, and Fig. 13 is an enlarged central vertical section of the guide cable reel.

70 For the purpose of illustration I have shown in the drawing a mining machine of which A indicates the main frame as an entirety, B the cutting apparatus extending from the inner end thereof and supported 75 thereby, C the feeding and guiding mechanism for advancing the cutting apparatus and machine either longitudinally or laterally, D the motor mechanism, and E the auxiliary parts employed when it is desired to have the cutting apparatus advanced into the coal transversely to the face thereof.

75 The main frame may be of any suitable construction as far as some features of my invention are concerned, but, for reasons which will later appear, I prefer a construction of the character shown. This construction comprises a shoe 1 adapted to rest upon the ground with freedom to slide freely in 80 all directions, longitudinally arranged angle bars or plates 2, 2 secured to said shoe at either side thereof and a suitable platform 3 resting upon and secured to said longitudinal side bars. 4, 4 are webs or plates depending from the platform 3 and carrying at their lower ends the laterally turned longitudinally extending cutting apparatus guides 5, 5. The main frame thus constructed constitutes a box which is closed on all 85 sides except the inner and outer ends.

90 It will be observed on reference to Figs. 3 and 4 that the platform 3 extends at its outer end beyond the bottom plate or shoe 1 and that the side plates 2 are correspondingly cut away. In other words, the outer end of the upper platform part of the main frame overhangs considerably.

- The cutting apparatus comprises a longitudinally arranged horizontally disposed base plate 6, two longitudinally arranged horizontally disposed guide plates 7, above said base plate and spaced therefrom by the longitudinally arranged bars 8 so as to form a chain guide or recess 9, the parts just referred to being secured together in any suitable manner, as by rivets 10.
- 11 is an inner sprocket wheel mounted upon a vertical axle 11', and between the inner end of the base plate 6 and a top plate 12 suitably secured to the base plate and having an outwardly extending centrally arranged part 12' fitted snugly between the top bars 7, 7 of the chain frame.
- The motor D is suitably secured upon the platform 3 with its armature shaft 13 arranged longitudinally of the machine.
- 14 is a longitudinally arranged shaft, preferably having its axis in the vertical longitudinal plane of the axis of the chain frame. It is suitably mounted at either end in bearings 14', 14'', one of which is carried by a bearing standard 14^a suitably secured to the platform 3. The inner standard 14^a extends transversely of the machine in either direction from the shaft 14 for the purpose to be hereinafter described.
- 15 is a spur gear rigidly secured to the shaft 14 and meshing with a pinion 16 secured to the inner end of the armature shaft 13.
- 17 is a bevel pinion loosely mounted on the shaft 14 near the outer end thereof.
- 18 indicates a positive clutch interposed between the said shaft 14 and the bevel pinion 17, the longitudinally stationary element 18' of said clutch being secured to the said bevel pinion and the longitudinally movable element 18^a being applied to the shaft.
- 18^b indicates suitable mechanism for moving the element 18^a of the clutch in either direction.
- 19 is a vertically disposed shaft suitably mounted in bearings carried by the main frame of the machine and having its axis in the vertical plane containing the axis of the shaft 14.
- 20 is a bevel gear secured to the upper end of the said vertical shaft and in mesh with the bevel pinion 17.
- 21 is a sprocket drive wheel rigidly secured to the lower end of the vertical shaft 19.
- 22 indicates as an entirety an endless cutter chain or carrier extending around the sprocket drive wheel 21 and the inner sprocket 11 carried by the cutter frame, it being arranged at either side within the guides 9 of the said cutter frame and carrying laterally extending cutters 23 of any suitable construction. The cutter frame is supported from the main frame by the longitudinally arranged slides or guides 5 de-
- pending from the main frame and arranged to fit snugly between the base plate and the upper plate of the chain frame. The main frame and the chain frame are normally held from longitudinal movement relative to each other by mechanism indicated as an entirety by 24, which also serves as an adjusting means for moving the frames relative to each other to vary the tension upon the cutter chain. The adjusting mechanism 24 comprises a longitudinally arranged screw-threaded shaft 24' mounted near its inner end in a bearing in a depending plate 25 which is secured to the inner end of the main frame platform 3. Near its outer end it is fitted into a threaded nut 26 which is arranged between uprights or projections 27, 27' carried by the base plate 6. The inner end of this shaft is squared as indicated at 24^b to receive a suitable wrench for turning the shaft in either direction so as to extend the chain frame relative to the main frame or to force it in the opposite direction relatively thereto, as desired.
- 28 is a worm gear rigidly secured to the longitudinally arranged shaft 14 near the inner end thereof and between the bearing standard 14^a and the gear wheel 15 secured to the said shaft.
- 29 is a shaft arranged beneath the said shaft 14 and transversely of the main frame. It is suitably mounted in a bearing 29' secured to the platform of the said frame.
- 30 is a worm wheel secured to the inside end of the said transverse shaft 29 and in mesh with the worm 28 on the shaft 14.
- 31 is a worm rigidly secured to the outside end of the shaft 29.
- 32 is a longitudinally arranged shaft mounted near either end of the bearings 32', 32'', carried by bearing standards 14^a and 32^a, the latter being arranged parallel to the former and of substantially the same width and secured to the platform of the main frame. The axis of this shaft 32 is in a vertical longitudinal plane on the opposite side of the vertical longitudinal plane of the axis of the shaft 14 from armature shaft 13.
- 33 is a worm wheel rigidly secured to the outer end of the shaft 32 and in mesh with the worm 31 on the transverse shaft 29.
- 34 is a spur gear loosely mounted upon the shaft 32 adjacent to the bearing standard 14^a, and 35 is a gear wheel of greater diameter than the gear wheel 34 and loosely mounted upon the said shaft 32 adjacent to the bearing standard 32^a.
- 36 indicates as an entirety clutch mechanism for alternately connecting the gears 34 and 35 to the shaft 32. Of this clutch mechanism 36' indicates a longitudinally movable element splined to the shaft 32 and carrying at one end clutch jaws 36^a adapted to engage clutch jaws 36^b secured to the gear 35.

wheel 35 and at its other end clutch jaws 36^c adapted to engage with the clutch jaws 36^d carried by the gear wheel 34.

37 indicates as an entirely suitable mechanism for shifting the movable element 36' of the clutch in either direction at will.

38 is a longitudinally arranged drum shaft suitably mounted near either end in bearings 38', 38^a, in the bearing standards 14^a and 38^a respectively. The axis of this shaft is on the opposite side of the vertical plane containing the axis of the shaft 14 from the axis of the shaft 32.

39 is a gear wheel rigidly secured to the shaft 38 near one end thereof and in mesh with the gear wheel 34 on the shaft 32, and 40 is a gear wheel of smaller diameter than the gear wheel 39 and rigidly secured near the opposite end of the shaft 38 and in mesh with the gear wheel 35 on the shaft 32.

41 is a cable winding drum loosely mounted on the shaft 38 and preferably adjacent to the gear wheel 40 at the inner end thereof. The periphery of the cable drum may be spirally grooved as indicated at 41' to assist in the spooling upon it of a draft cable 44 which has one end suitably fastened to said drum. The drum is preferably connected to the shaft 38 by means of a friction clutch 41^a, one element of which is a ring or casing 41^b carried by the drum and extending outwardly therefrom; and the other element of which is a pulley or ring 41^c having its rim radially slotted at 41^d, as indicated.

41^e are adjustable wedges or expanders arranged between the sections of the rim at said slots and adapted to force the periphery of the rim into engagement with the inner walls of the ring 41^b in the well-known manner. By varying the adjustment of the expanders the clutch can be made to slip when the resistance to the rotation of the winding drum reaches any given amount.

43 is a pulley or sheave arranged to receive and guide the cable 44 as it is wound upon or is paid out from the drum 41.

42 is a bearing bracket secured to the side plate 2 adjacent to the drum 41.

42' is a longitudinally arranged shaft suitably supported by the laterally extending arm 42^a of the said bracket.

43 is an idler pulley on the shaft 42'. When the machine is in operation and is being advanced along the coal, this pulley guides the cable while it is being wound upon the drum.

When the machine is in operation it is advanced along the face of the coal by tension in the draft cable 44 due to the rotation of the drum 41. Under the action of this forward draft, the outer end of the machine tends to swing forward relative to the cutter frame because of the resistance which the coal offers to the advance of the cutters. To

overcome this tendency and maintain the machine in proper working position relative to the face of the coal, I use a cable or flexible holder for the outer end of the machine supplemental to the main draft cable 44. 70 Such cable is indicated at 56. Its forward end is secured to the jack at 45. From this jack it extends backward to the machine and across the inner end thereof to the guide pulley or sheave 53 preferably located near 75 the inner right hand corner of the frame. From here it extends outward to a pulley or sheave 53' on the outer rear corner of the frame and thence it is carried to a stationary holder behind the machine. As shown, this 80 stationary holder consists of a winding drum or reel 46 mounted on a base 47 which is adapted to be secured in position by any suitable post or screw jack at 48. The base 47 has standards 47', 47'' which carry a shaft 85 46^a upon which the reel is rotatably mounted. On one side of the reel is a flange with ratchet teeth 46', and a pawl lever 46^b constitutes means for manually turning the reel 90 to wind up on cable 56. A detent 47^a normally prevents the reel from unwinding, but can readily be disengaged to permit an unwinding of the cable 56.

With the cable 56 arranged as described, and as shown in Fig. 11, it is clearly adapted to prevent the outer end of the machine from swinging forward because of the reaction of the coal, as above referred to, and to maintain the machine at a given angle to the face of the coal as the undercutting proceeds. At the same time, if it is desired to change the angle of the machine, this can readily be done by means of the winding reel 46, for by turning the reel so as to pay out the cable 56, the outer end of the machine 105 will be allowed to swing forward correspondingly, and by turning the reel in the opposite direction, so as to shorten the cable 56, the outer end of the machine will be 110 swinging correspondingly rearward.

In longwall mining an undercut is usually easily started at a free face, but in room and pillar work an entering or "sumping" cut must be made in order to get the cutting apparatus under the coal; this entering cut 115 being made adjacent one or the other of the ribs constituting the side walls of the room. With my improved machine the sumping cut is made by feeding the machine longitudinally forward so as to project the cutting apparatus into the coal in a manner like that in which "breast" mining machines are operated. For this purpose I have devised the combined jack and cutter mechanism guide E illustrated in Figs. 7, 8, 9 120 and 10.

54 is a base plate of the said jack stand adapted to rest upon the floor of the mine closely adjacent to the coal face and at an angle thereto, as shown. Near either end of 125

this base plate is a pair of upwardly extending arms or lugs 55 supporting between them a shaft or pivot 56^a with its axis arranged longitudinally of the base plate.

57 indicates the jack proper comprising a shank or bar 57' forked at its lower end as indicated at 57^a, the ends of each arm of said fork being recessed as indicated at 57^b to fit over one of the shafts 56^a on the base plate. The upper end of the jack shank is screw threaded at 57^c to receive a screw threaded hand adjusting wheel 58.

59 is a pointed head for the jack swiveled on the upper end of the jack 57' and bearing against the upper face of the hub of the wheel 58 by means of which it is adjusted longitudinally of the shank.

54' is an arm or plate extending laterally from the base plate 54 and carrying the upright bracket 54^a which at its upper end is bifurcated as indicated at 54^b to receive one end of a swinging arm 60, which is pivotally connected to the uprights 54^a by means of a bolt 60'. At its free end the arm 60 has pivotally connected to and depending from it a slide 61 which is longitudinally grooved at either side to receive the adjacent longitudinal guide bars 12^b on the chain frame. These guide bars 12^b are rigidly secured in position by means of bolts 12^c screw-threaded into inwardly projecting lugs 12^d carried by the base plate 6 of the chain frame. The slide 61 may be introduced into position within the said top plate at the ends of the guides 12^b adjacent the main frame. The slideable connection between the slide 61 and the outer frame permits the longitudinal movement of the cutter frame relative to the slide while tending to prevent the lateral movement in either direction of the cutter frame relative to the base plate 54. It will thus be seen that when the jack stand is securely fastened in position by means of the jack 57, the cutter frame may be caused to travel forward in a substantially straight line. When the slide 61 reaches the ends of its guides 12^b it may be swung upwardly out of the path of travel of the cutter frame.

50 To operate the machine for room and pillar work it is unloaded at the corner of the room where it is desired to begin the cut and with the end of the cutter frame closely adjacent to the face of the coal. The combined jack and cutter frame guide E is then clamped securely in position on the left hand side of the cutter frame near the end thereof, as indicated in Fig. 10, the slide 61 having been introduced into its guide in the top plate of the said frame. The cable 44 is next carried inward from the drum 41 along the side of the machine to the inner end of the jack frame and pivotally connected thereto, as indicated at 62, a suitable idler guide 63 serving to direct the course of the

cable from the drum toward the said jack stand. This idler guide 63 is mounted on a journal 64 carried by a U-shaped bracket 65 which is pivotally mounted on a longitudinal shaft 66 carried by lugs 67, 67, projecting laterally from the main frame. The U-shaped bracket 65 has a laterally extending lug or projection 65' which is adapted to engage with the platform of the main frame to limit the inward travel of the bracket 65 about the axis of the shaft 66, as indicated in Fig. 6. The bracket 65 may be readily detached by removing the shaft 66, whenever it is not desired to use the idler guide 63. The motor having been started, the cutting apparatus and the slow-feed gearing of the winding drum are then connected to the motor by clutches 18 and 36 respectively. The drum 41 winds up on the cable and pulls the main frame of the machine toward the coal face, the cutting apparatus simultaneous undercutting the coal. The cutter frame guiding mechanism tends to insure that the cutting apparatus will be moved inward in a substantially straight line. When the slide 61 reaches the ends of the guides 12^b it is withdrawn therefrom and the machine will feed inward if necessary without further guiding. The sumping cut having been completed, the machine is stopped, the guide jack E and the idler guide 63 removed, the feed cable 44 extended to the far rib and secured to an anchor or jack 52. The winding reel 46, with the cable 56 thereon, is then secured in position adjacent the rib at which the cut is started, and the loose end of said cable is carried around guide sheaves 53' and 53 on the machine frame and thence forward along the coal face to the distant rib where it is fastened to the jack 45. See Fig. 11. The motor is now started and clutches 18 and 36 closed so as to drive the cutters and the winding drum 41. Ordinarily, the winding drum is driven through the slow speed gearing when the cutters are at work, the high speed gearing being used when the propelling cable is employed to move the machine about in the room. The rotation of the winding drum 41 creates tension in the cable 44, tending to advance the machine along the face of the coal. Under the action of the draft of the cable 44 and the resistance which the coal offers to the cutters, the outer end of the machine tends to swing forward relative to the inner end, but this is resisted by the guiding cable 56. This will be readily understood from an inspection of Fig. 11, for it will be seen that the outer end of the machine cannot swing forward unless that part of the cable 56 extending between the guide sheave 53' and the stationary winding reel 46 is in some way lengthened. In other words, as long as the winding drum 46 is locked against rotation, the machine, under the ac-

tion of the draft in the propelling cable 44 and the reaction of the coal on the cutters, is caused to advance at a fixed angle to the face of the coal.

- 6 At the same time, it is possible to readily change the angle of the machine to the face of the coal whenever this is desirable to meet varying conditions of the material being cut, of the floor of the mine, etc. Thus, 10 if it is desired to angle the outer end of the machine rearward, the ratchet lever 46^b can be actuated to rotate the drum 46 in the direction to wind up the cable 56, thus drawing the outer end of the machine rearward. 15 Such a movement of the outer end of the machine can, of course, be effected with the least effort if the motor is stopped, or the driving clutch 36 opened, so as to ease the tension in the propelling cable. On the 20 other hand, if it is desired to angle the outer end of the machine forward relative to the inner end, this can be done by disengaging the detent 47^a and permitting the reel 46 to turn so as to pay out the cable 56, thus 25 lengthening that part of the cable 56 extending between the guide sheave 53' and the reel 46 and permitting the outer end of the machine to swing forward correspondingly.

- 30 I have referred above to the propelling and guiding mechanism as adapted to maintain the machine at a given angle to the face. Under some conditions, however, as for example, when impurities of great density 35 and hardness are encountered by the cutters, it is desirable that the machine have greater flexibility in its movements. When the cutters meet abnormally great resistance, there is danger of breakage of some part or parts 40 of the machine if the mechanism is such that an unvarying movement of the machine is necessary regardless of the resistance encountered.

- In the case of my improved machine the 45 propelling reel 41 is driven from the motor through the friction clutch 41^a which can be set to slip when the tension in the draft cable 44 reaches any amount determined upon. Therefore, when the cutters encounter an abnormally high resistance due to 50 hard impurities or the like, such increased resistance, if sufficiently great, will result in slippage between the parts of the friction clutch 41^a so that the winding reel 41 is driven at a slower speed. Thus, the 55 advance of the machine is retarded and the cutters are given an opportunity to cut through the harder material.

- In all of the advancing and swinging 60 movements of the machine it is free to slide in any direction over the floor of the mine, and in usual practice this free movement of the machine is facilitated by the use of flat skids. These skids, which are in the form 65 of thin metal plates a few inches wide, are

laid upon the floor of the mine in the direction of the machine's advance and, by affording a hard smooth surface for the main frame, greatly facilitate the movement of the machine.

70 It will be understood that the friction clutch 41^a can be set to give way under any stress within a reasonable range so that the machine can be made to cut through minor impurities or hard streaks without slippage 75 occurring. In some deposits of coal, impurities are encountered which are of such great density and hardness or so extensive that it is not desirable to attempt to cut through them, even at the reduced speed 80 permitted by the slippage of the clutch 41^a. In some such cases it is possible to carry the undercut over or under the obstruction, and my improved machine is well adapted to work under such conditions. Thus, if a roll 85 is encountered it may be found possible to back the machine off along the face to a suitable distance from the obstruction and then by blocking up the skids, which, as previously noted, are commonly used with 90 such machines, the cutters may be guided in an upwardly inclined path over the obstruction and then gradually downward again to the normal level.

95 Reference has already been made to the box-like construction of the main frame of the machine. This I regard as a feature of much practical importance. During the cutting operation the fine coal or slack which is formed is dragged out of the kerf by the cutters and must be handled or disposed of in such a way as not to clog or interfere with the cutters or other working parts of the machine. In my improved construction this fine coal is drawn into and outward through 100 the box-like bed frame to the outer end of the machine by the cutters. There as the cutter chain rounds the driving sprocket wheel, the fine material falls either quite clear of the machine as it advances, or, if 110 it is not delivered entirely clear of the machine, it is possible for the machine runner or his helper to readily shovel it away because the cutting away of the side plates of the frame at the outer end thereof leaves a 115 free space adjacent the driving sprocket wheel and beneath the upper platform part of the frame which permits ready and effective use of the shovel for the purpose stated. Furthermore, it will be observed 120 that with the exception of the cutters and the sprocket wheel which drives them, all of the working parts—gears, winding drums, clutches, motor, etc.—are mounted above the upper platform part of the frame 125 so as to be fully protected from contamination with the fine coal or slack which cannot rise and enter any of these working parts during its passage from the face outward to the point where it is delivered by 130

the cutters free of the machine. In this connection it will be observed that practically all of the gears, shafts and clutches constituting the driving mechanism are grouped compactly together on one part of the frame platform while the motor occupies another part. This arrangement of the motor and the driving gearing greatly facilitates the complete protection of the gearing from dust because it makes it possible to inclose the gearing by means of a simple protecting casing.

In the foregoing description of the operation of the machine its use in room and pillar mining was considered. It will be obvious without further detailed description that the operation in making an under-cut along the face would be essentially the same in longwall mining. Ordinarily, in longwall mining it is not necessary to make an entering or sumping cut because the cut can be started at a free face.

Referring to Figs. 1, 2 and 5, I have shown means by which power may be transmitted to gearing on a suitable mining machine truck upon which the mining machine may be mounted, said gearing being for the purpose of propelling the truck. This mechanism comprises a transversely arranged shaft 68 in axial alignment with the transverse shaft 29, the inside end of which latter shaft is fitted into a recess 68' in the inside end of the shaft 68.

69 is a positive clutch one element of which 69' is secured to the shaft 29 and the other element 69" is carried by the inside end of the shaft 68. The shaft 68 is suitably supported on a bearing 70 secured to the main frame.

71 is a sprocket wheel rigidly secured to the outside end of the shaft 68 and adapted to be connected with the propelling mechanism on the mining machine truck. When not required in use the shaft 68 may be removed from the machine by drawing it longitudinally out from the bearing 70.

It will be observed that the guide cable 56 loosely engages the guide sheaves 53, 53', and can readily be disengaged from the machine frame. Also, the winding reel 46 and the base upon which it is mounted are separate from the machine frame. Therefore, when the machine is to be moved about in the room, the cable 56 can be disengaged from the guide sheaves and wound compactly upon the reel 46 leaving the machine free and unencumbered, so that it can readily be dragged over the floor by means of the winding reel 41 and its cable 44. In the case of prior machines in which loose ended chains or cables are employed, considerable inconvenience has been experienced in handling the machines under the conditions now referred to on account of

the cumbersome nature of the loose chains or cables.

The construction of the devices for effecting the sumping cut, as shown and described, is such as is set forth and claimed in the application filed by me September 20, 1906, Serial No. 335,453; and I do not herein present claims for any of the said matters of construction, the claims herein relating to the construction and arrangement of the parts by which the machine is propelled and guided or adjusted in its positions relative to the coal and relative to its line of travel.

What I claim is:

1. In a mining machine, the combination of a main frame, cutting apparatus carried thereby, a winding reel on the frame, a cable on the reel for propelling the machine when it is in operation and adapted to be fastened to a stationary holder in advance thereof, guiding mechanism comprising a second cable adapted to be anchored in advance of the machine, a plurality of guide sheaves on the frame over which the second cable passes, one of said sheaves being disposed with respect to another toward the outer end of the frame, and a relatively stationary take-up mechanism to which the guide cable is secured.

2. In a mining machine, the combination with a main frame and cutting apparatus carried thereby, said frame being adapted to move laterally parallel to the face of the coal being cut while the cutting apparatus moves laterally under the coal, of a winding reel mounted on the frame adjacent to the coal face, a propelling cable connected to the said reel on the frame and adapted to be secured to a stationary holder in advance of the machine, a second cable independent of the said propelling cable having one end normally secured to a stationary holder in front of the machine, a plurality of guiding sheaves on the frame over which the second cable passes, one of said sheaves being disposed with respect to another toward the outer end of the frame, and a winding reel secured stationarily behind the machine, to which reel one end of the guide cable is secured.

3. In a mining machine, the combination with a main frame, and cutting apparatus carried thereby, said frame being adapted to be moved laterally along the face of the coal to be cut and the cutting apparatus to move laterally therewith while under the coal, of a winding reel mounted on the inner end of the frame, a propelling cable secured to said reel and adapted to be extended thence forward to a stationary holder, a motor disposed on the outer side of the said reel, a guiding or alining cable independent of the said propelling cable secured to a

- stationary holder in front of the machine, a guide sheave for said guide cable mounted on the inner end of the frame, a second guide sheave for said guide cable mounted on the frame toward the outer end thereof with respect to the first named sheave, and a winding reel for the guide cable stationary mounted separate from the frame.
4. In a mining machine, the combination of a main frame, cutting apparatus carried thereby, a winding reel on the frame, a cable on the reel for propelling the machine when it is in operation and adapted to be fastened to a stationary holder in advance thereof, guiding mechanism comprising a second cable independent of the said propelling cable and adapted to be anchored in advance of the machine, a plurality of guide sheaves on the frame over which the guide cable passes, and a relatively stationary take-up mechanism to which the guide cable is secured.
5. In a mining machine, the combination of a main frame, cutting apparatus carried thereby, a winding reel on the frame, a cable on the reel for moving the machine along the face of the coal and adapted to be fastened to a stationary holder in advance of the machine, guiding mechanism comprising a second cable stretched along the face of the coal and having one of its ends anchored at one side and its other end anchored at the other side of the machine, and a plurality of guide sheaves on the machine over which the second cable passes, one of said sheaves being disposed with respect to another toward the outer end of the frame.
6. In a mining machine, the combination of a main frame, cutting apparatus extending from the inner end thereof, a winding reel on the frame, a cable secured at one end to said reel and adapted to have its other end fastened to a stationary holder in advance of the machine to propel it along the face of the coal, means for retarding the outer end of the frame comprising a cable independent of the said propelling cable, and manually controlled means associated with the last named cable and separate from the machine frame for positively swinging the machine to various angles to the face of the coal in one direction.
7. In a mining machine, the combination of a main frame, cutting apparatus extending from the inner end thereof, a winding reel on the frame, a cable secured at one end to said reel and adapted to have its
- other end fastened to a stationary holder in advance of the machine to feed it along the face of the coal, a second cable independent of the feeding cable extending along the face of the coal and arranged to exert a rearward draft on the outer end of the machine frame, stationary securing means at the rear end of said second cable for sustaining the draft thereof, and means for lengthening or shortening that portion of the last named cable which lies between its point of draft on the machine frame and the said stationary securing means.
8. In a mining machine, the combination of a main frame, cutting apparatus extending from the inner end thereof, a winding reel on the frame, a cable secured at one end to said reel and adapted to have its other end fastened to a stationary holder in advance of the machine to propel it along the face of the coal, and means for guiding the machine comprising a second cable independent of the propelling cable and adapted to extend along the face of the coal, guide devices on the machine frame with which the second cable engages, and a winding reel for said guide cable by which the cable can be drawn to positively angle the machine in one direction, the last named winding reel being separate from the machine frame, and the guide cable having a loose and readily disengageable engagement with its guide devices on the machine frame, whereby the winding reel and guide cable can readily be disconnected from the machine frame.
9. In a mining machine, the combination of a main frame, cutting apparatus extending from the inner end thereof, a winding reel on the frame, a cable secured at one end to said reel and adapted to have its other end fastened to a stationary holder in advance of the machine to propel it along the coal face, means for retarding the outer end of the frame comprising a cable independent of the said propelling cable, and manually controlled means separate from the main frame associated with the last named cable for causing it to hold the machine at either of several angles to the face of the coal while it is being normally propelled by the other aforesaid cable.

In testimony whereof I affix my signature,
in presence of two witnesses.

WALTER F. TROTTER.
